APPARATUS FOR CONTROLLING HEATING SYSTEMS

Joseph T. Lewandowski, Chicago, Ill., assignor to
 Minneapolis-Honeywell Regulator Company,
 Minneapolis, Minn., a corporation of Delaware

Application August 27, 1938, Serial No. 227,172

14 Claims. (Cl. 236—46)

My invention relates to automatic control of heating systems and is more particularly directed to the control of steam heating systems including the so-called steam, vapor, and vacuum types.

Heretofore satisfactory control of steam heating systems has not been generally attained, particularly in systems employing intermittent operation of a fuel burner or the like because of the tendency of the burner to be shut off before all parts of the system have been properly supplied with heating medium. Under thermostatic control the burner will often be shut off before sufficient boiler pressure has built up to insure that an adequate supply of heating medium has been forced to upper floor radiators. A boiler responsive thermal element cannot be relied upon to properly shut down the burner because fluctuations in water level, surging, and boiler currents will frequently cause a response by such an element when there is not a corresponding proportional vapor pressure in the system necessary for proper heating at all points.

In my system I overcome these difficulties by utilizing a pressure responsive device to stop the burner, thereby insuring that once the burner has been started a satisfactory pressure necessary to cause all parts of the system to be adequately supplied with heating medium will be attained before the burner is stopped.

On the other hand, a pressure responsive device, particularly in vacuum systems cannot be satisfactorily relied upon for starting the burner. For instance, when a vacuum responsive device is arranged to start the burner upon attainment of a predetermined vacuum in the system, operation is not satisfactory because any number of factors may intervene to break the vacuum preventing its reaching the necessary value. For example, leaks in the system or opening of the system for inspection or repairs will destroy the vacuum and preclude proper starting of the burner. Therefore in my combination I employ a temperature responsive device for starting the burner which will do so whether or not a predetermined vacuum has been established in the system. My system, therefore, provides for positive control, starting the burner immediately upon a need for heating and maintaining it in operation until after assurance that a condition has been reached whereby heat has been adequately delivered to all parts of the system.

My system has various other important aspects and features which will become apparent from the detailed specification following. It is to be understood that my invention is applicable

to various types of heating systems, not being limited to any particular type of construction or form of fuel or burner apparatus. It is my purpose to secure protection by Letters Patent on all the various novel features, phases, and aspects of my invention as set forth in the appended claims.

Among the objects of my invention are:

10 To provide an efficient and reliable automatic control system and method for heating systems employing a vaporizable heating medium.

15 To provide a control system for heating systems employing vaporizable heating medium which will insure that all parts of the system are properly supplied with heating medium upon each demand for heating.

20 To provide an automatic control system for heating systems employing a vaporizable heating medium in which heating is initiated in response to a device measuring the load upon the system and in which heating cannot be terminated before pressure within the system has reached a predetermined value.

25 To provide an automatic control system for heating systems employing a vaporizable heating medium wherein heating is initiated in response to temperature and continued under control of a pressure controller which may stop and restart the system if the temperature is such as to indicate the need for further heating.

30 To provide a steam heating system having a firing device started by a return line temperature controller and maintained in operation by a pressure responsive device.

35 To provide a stoker fired steam heating system in which the stoker is started by a temperature controller and may be stopped by a pressure controller and which has an automatic device for starting and stopping the stoker to keep the fire in the furnace from going out.

40 To provide a stoker fired steam heating system having a control system including a temperature controller for starting the stoker and a pressure controller for stopping the stoker and an automatic device for starting and stopping the stoker but which cannot stop the stoker if it was started by the temperature controller.

45 To provide an improved control system for heating systems in which heating is initiated in response to temperature of heating medium as compensated by outdoor temperature and is continued at least until a predetermined condition of the heating medium is attained.

50 To provide an improved control system for heating systems employing vaporizable heating

medium wherein an electrical fuel supplying device is energized by a temperature controller and upon starting of the device a maintaining circuit therefor is established and is controlled independently of the temperature controller.

To provide a stoker fired heating system in which heating is initiated in response to temperature of heating medium as compensated by outdoor temperature, heating being then controlled in response to pressure of heating medium and the system having an automatic device for starting and stopping the stoker when outdoor temperatures are such that heating is not required.

To provide an improved method of control of heating systems employing a vaporizable heating medium.

Referring to the drawing:

Figure 1 represents my control system applied to a stoker fired steam heating system.

Figure 2 is a detail plan view of a portion of the control apparatus, and

Figure 3 is a sectional detail view of another portion of the control apparatus.

I have chosen to describe in detail as an illustrative embodiment of my invention a one-pipe steam heating system as shown in Figure 1, embodying my improved control arrangement.

Numerals 1 designates a furnace or boiler forming part of a steam heating system for a building structure, a portion of which is shown at 2. Connected to the boiler 1 is a riser or supply pipe 3 which has branch pipes connected thereto, two of which are shown at 4 and 5 and to which are connected radiators as indicated at 6 and 7 on various floors of the building. That is, the pipes 4 and 5 may supply steam to radiators similar to the radiators 6 and 7 on higher floors of the building. The radiators 6 and 7 are equipped with suitable air valves 8 and 9 which operate in a well known manner to exclude air from the system without permitting the passage of steam therethrough. The pipe 3 extends through a steam trap 10 located beyond the pipes connecting to the various radiators and the continuation of the pipe 3 forms a return pipe designated 11 which connects to the lower part of the boiler. From the above it will be apparent that the present system is of the type commonly designated as a one pipe system. It is to be understood however that the present disclosure is exemplary only and the invention is equally applicable to other types of systems.

The furnace or boiler 1 is fired by an automatic stoker 13 which is electrically driven, the motor for driving this stoker having electrical terminals 14 and 15. My invention is particularly well adapted for systems employing a stoker for supplying fuel in solid form to the furnace but other forms of fuel supplying devices or boilers may be utilized.

Associated with the boiler so as to be responsive to the pressure therein is a pressure actuated switch generally designated at 16. The pressure responsive switch 16 comprises an expansible bellows 17 responsive to the pressure within the boiler and which acts upon a pivoted lever 18 carrying a mercury switch 19. The lever 18 is biased in closing direction of the mercury switch 19 by a coil spring 20 which is usually made adjustable in switches of this type. The switch 19 is normally closed and when the boiler pressure has risen to a predetermined value which may be adjusted by adjusting the tension

spring 20, the lever 18 is rotated in a clockwise direction sufficiently to open the switch 19.

In controlling my system I employ for primary control a thermostat responsive to the temperature of the return line 11 which temperature is a measure of the amount of heat being used for heating the building. As the heating load upon a building increases, more steam will be required in the various radiators for heating and consequently the temperature of the condensate in the return line will rise. Therefore, I use an outdoor temperature responsive thermostat for compensating the control point of the return line thermostatic responsive mechanism so as to raise its control point as the outdoor temperature falls. Thus as the outdoor temperature goes down indicating a greater heating load, I supply more steam to the system as determined by the raised control point of the return line thermostat. The thermostatic control mechanism which I employ is of the electrical proportioning type and is generally designated at 23. The proportioning mechanism 23 comprises a balanced relay having a pair of windings 24 and 25 associated with an armature 26. The armature 26 is arranged to operate a switch arm 27 cooperating with fixed electrical contacts 28 and 29. When the coils 24 and 25 are equally energized the armature 26 assumes a position as shown wherein this switch arm 27 does not engage either of the contacts 28 or 29. When the energization of coil 25 preponderates over that of coil 24, the switch arm 27 engages contact 29 and when the energization of coil 24 preponderates the switch arm 27 engages the contact 28. Primarily controlling the balanced relay is a controller generally designated at 30 comprising an expansible bellows 31 connected by a capillary tube 32 to a thermostatic bulb 33 arranged adjacent to the return line 11 of the heating system. The bulb 33, the capillary tube 32, and bellows 31 are filled with a temperature responsive medium, which upon expansion or contraction causes the bellows 31 to actuate a pivoted lever 34 having two integral arms 35 and 36. The lever 34 is biased in a counter-clockwise direction about its pivot by coil spring 37 which is preferably made adjustable. The arm 35 forms a slider cooperating with a slide wire resistance 38 so as to form a potentiometer, and the arm 36 forms a slider cooperating with a slide wire resistance 39. Numeral 42 designates a second controller similar to the controller 30 and comprising a thermostatic device having an expansible bellows 43 connected to an outdoor temperature responsive bulb 44 by a capillary tube 45. Bellows 43 is actuated in response to outdoor temperature in a manner similar to that in which bellows 31 is actuated in response to return line temperature. The bellows 43 actuates a pivoted lever 46 having an angular arm 47 which forms a slider cooperating with a slide wire resistance 48. The lever 46 is biased in a counter-clockwise direction by a coil spring 49 which may be made adjustable the same as the coil spring 37. The two coils 24 and 25 of the balanced relay are connected in series and the slide wire resistance of controller 30 is connected across series connected coils 24 and 25 by wires 51 and 52 in series with which are interposed the protective resistances 53 and 54. The slide wire 48 of controller 42 is connected in parallel with the slide wire resistance 38 and the series connected coils 24 and 25 by wires 55 and 56 which

connect the ends of slide wire 48 to wires 51 and 52, respectively.

The mid point of the resistance 39 is connected to the juncture of coils 24 and 25 by a wire 58 and the slider 47 is connected to wire 58 by a wire 59, the latter wire having a compensating resistance 60 interposed in series therewith. The balanced relay may control various types of mechanism but in my arrangement it controls a relay generally designated at 61. The relay 61 comprises an energizing coil 62 and a neutralizing coil 63, both of the coils being associated with an armature which is arranged to operate switch arms 64 and 65. The switch arm 64 cooperates with a fixed electrical contact 66 and the switch arm 65 cooperates with fixed electrical contact 67. Switch arms 64 and 65 engage with their associated contacts when the coil 62 is energized and disengage from their associated contacts when neither of them are energized or when they are both energized. Power for the mechanism designated at 23 is supplied by a voltage step-down transformer generally designated at 70 and comprising a primary winding 71 which may be connected to a suitable source of external power (not shown) and a secondary winding 72. One end of the secondary winding 72 is connected to one end of the coil 24 by a wire 73 and the other end of secondary 72 is connected to one end of the coil 25 by a wire 74, a portion of wire 75, and wire 52. The wire 75 connects to the fixed contact 29 and the fixed contact 28 is connected by a wire 76 to one end of coil 63. Opposite ends of the coils 62 and 63 are connected by a wire 77 and one end of coil 63 is connected to the juncture of wire 73 and coil 24 by wire 78. The other end of coil 62 is connected to switch arm 27 by a wire 79 which has a branch wire 80 connected to switch arm 64. The fixed contact 66 is connected to the juncture of the coil 25 and wire 52 by a wire 81.

I will describe the operation of the temperature responsive mechanism 23 in controlling the switch 65 in the description of operation following. The switch 65 as will later appear is arranged to control an electrical relay indicated generally at 83 and which relay in turn controls the stoker 13. The relay 83 comprises a coil winding 84 cooperating with an armature arranged to operate switch arms 85 and 86 cooperating with fixed electrical contacts 87 and 88, respectively. The armature of relay 83 also actuates a pivoted lever arm 89 to which is secured by riveting or the like, a flexible metal blade 90. Numeral 91 designates an angular lever having the shape shown on the drawing and pivoted at 92. The lever 91 has a generally horizontal portion 93 having a slidable weight 94 engaged thereon which biases the lever 91 in a clockwise direction about its pivot. Integrally formed on a portion of the lever 91 is a lug or finger 95 which is engaged by the flexible blade 90 when the relay 83 is energized causing arm 89 to move to the left thereby moving the lever 91 in a counter-clockwise direction a certain amount. The lever 91 also has an extending portion 96 at the end of which is an operating finger 97 which will be more specifically referred to later in the specification.

Numeral 100 designates generally timing mechanism which cooperates automatically in the control of the relay 83 and consequently the stoker 13. The timing mechanism comprises an electric timing motor having an armature 101 and a winding 102. The timing motor drives a

pair of cams 104 and 105 through a suitable gear train 103 so as to cause them to rotate through one revolution in an hour. The cams 104 and 105 are frictionally mounted on an axle or shaft 5 which is driven, by the gear train 103 and the cams may be rotated with respect to the shaft. The cams 104 and 105 are rotated in a clockwise direction and the contour of the cam 105 as may best be seen in Figure 1 wherein cam 105 is 10 shown shaded has two abrupt drop-offs at 106, the drop-offs being spaced apart a small amount. Cam 105 has two similar drop-offs diametrically opposed on the opposite side of the cam. The cam 105 has a rise at 107 from a portion of smaller diameter to a portion of larger diameter and a similar rise diametrically opposed on the opposite side of the cam. The cam 104 has an abrupt drop-off at 108 and a similar abrupt drop-off diametrically opposed on the opposite side of the cam. The cam 104 also has two diametrically opposed projecting portions 109 and 110 which form rises in the cam contour. It will be seen that the portions of the cam contour of cam 104 15 between the drop-offs and the projecting portions is of slightly smaller diameter than the remaining portions of the cam contour. The projecting portion 110 is integrally formed as part of a plate 112, the shape of which may best be seen on Figure 1, one edge of this plate 20 forming a portion of the contour of cam 104 of relatively smaller diameter. The plate 112 is secured to the cam 104 by means of a screw 113 and a pin 114 which extends through a corresponding opening in the plate 112. The edge of 25 the plate 112 nearest the center of the cams is circular and has the same radius as those portions of the contour of cam 104 of larger diameter. Thus by removing the plate 112 and turning it over this circular edge can be made part 30 of the cam contour so that the cam 104 will be entirely circular except for the abrupt drop-off and rise 109 diametrically opposed to the drop-off 108 and projection 110. In the cam 104 is 35 an arcuate slot 116 and a second arcuate slot 117. Numeral 118 designates a handle which is screwed onto a pin extending from the cam 105 through the arcuate slot 118 and which engages cam 104. By loosening the handle 118, cam 104 40 may be rotated relatively to cam 105 and the cams may then be secured in their relative positions by tightening the handle 118. Numeral 119 indicates a lug forming a pointer which is struck up from the surface of cam 105 and the end of which is disposed within the arcuate slot 45 117. The portion of the cam 104 adjacent to the arcuate slot 117 is graduated in figures from 50 1 to 7, as seen on Figure 1, these figures designating minutes for a purpose which will presently 55 become apparent.

60 Numeral 120 designates an arbor or spindle upon which is mounted a cam follower 121 so as to rotate therewith. Numeral 122 (see Figure 2) is a similarly shaped cam follower mounted on the arbor 120 so that it may rotate thereon. The cam followers 121 and 122 are made of insulating material and the cam follower 121 follows the contour of cam 104 while the cam follower 122 follows the contour of cam 105. Also carried 65 by the arbor 120 and arranged to rotate therewith is a lever 123. It will be understood that the arbor 120 and all the apparatus comprising the timing mechanism may be mounted on a suitable panel board 124 and the lever 123 has a pin 125 extending through an opening 124' in 70 this panel board. The pin 125 is connected by 75

a coil spring 126 to a pin 127 formed on the panel board and the coil spring continually biases the lever 123 and arbor 120 in a counter-clockwise direction causing the cam follower 121 to bear against the contour of cam 104. Encircling the arbor 120 between the cam followers 121 and 122 is a coil spring 130 which is attached to the cam followers in a manner to urge the cam follower 122 in a counter-clockwise direction against the contour of cam 105. Numeral 131 indicates a small latch member which is pivoted to the end of the lever 123 (see Figure 2) and which has a finger 132 which engages in a notch 133 in the end of the lever 123. Secured to the cam follower 122 is a contact strip 134 at the ends of which are fixed electrical contacts 135 and 136. The center part of the strip 134 is fastened to the cam follower 122 by a screw 137 to which an electrical wire is connected. Secured to the cam follower 121 by screws 138 and 139 are contact brackets 140 and 141, respectively, the contact bracket 140 carrying an electrical contact 142 and the contact bracket 141 carrying an electrical contact 143.

It will be seen that the operating finger 97, previously described, is disposed adjacent to the latch member 131 with the parts in the position shown in Figure 1. The portion of the latch member 131 adjacent to the finger 97 is more or less pointed and when the relay 83 is energized causing arm 89 and blade 90 to move to the left so as to engage lug 95 rotating lever 91 counter-clockwise the finger 97 will engage latch member 131 moving it slightly about its pivot and riding over its pointed end so that finger 97 engages the underside of the end of lever 123. With the parts in this latter position, the finger 97 prevents the lever 123 and consequently the arbor 120 from rotating in a counter-clockwise direction. Further description of this mechanism will be made in the general description of operation following.

Also driven by the armature 101 of the timing motor is a suitable gear train generally designated at 147 which drives a time dial indicated at 148. Forming part of the gear train 147 is a pinion gear 149 meshing with a larger gear 150 as may be seen on Figure 2, the gear train being arranged to rotate the time dial 148 once in twenty-four hours. The gear 150 is secured to a hub 151 which in turn is rotatably mounted on a spindle or arbor 152 which may be carried by the panel board 124 previously referred to, the pinion 149 extending through an opening 153 in the panel board. The time dial 148 is secured to the hub 151 and is spaced from the gear 150 by a spacing member 154. Half of dial 148 is shaded as seen in Figure 1 and the shaded half is graduated in hours from 1 to 12 representing the hours from 12 a. m. noon until 12 p. m. midnight. The other half of the time dial 148 is not shaded and the periphery of this half is graduated in hours from 1 to 12 designating the hours from 12 p. m. midnight to 12 a. m. noon. Rotatably mounted on the hub 151 are two half dials 155 and 156. The half dial 156 is shaded and its periphery is graduated in hours from 1 to 12 representing the afternoon part of the day, this half dial being utilized for setting the time of night, shut-downs as will presently become apparent. The half dial 155 is not shaded and is graduated from 1 to 12 representing the hours in the morning half of the day, this half dial being utilized for adjusting the time at which the system is restarted after a night shut-down as will presently become apparent. The half dial 156 has an arcuate slot

as may be seen in Figure 1 through which the graduations on the half dial 155 are visible. Numeral 157 represents a ring having a pointer 158 integrally formed therewith, this ring being splined onto the hub 151 so that the pointer 158 may not be rotated relatively to the hub. The half dials 155 and 156 and the ring 157 carrying the pointer are secured in relative position with respect to the hub 151 by a thumb screw 159 engaging on the end of the hub. By loosening the thumb screw the relative positions of the half dials 155 and 156 may be adjusted relatively to each other and to the time dial and by tightening the nut 159 these elements may be secured in the desired positions. A disc 160 is secured to the end of the arbor 152 and interposed between this disc, encircling the arbor and abutting against the end of the hub 151 is a coil spring 161. Thus by grasping the thumb nut 159, the arbor 151 and all the elements secured thereto may be longitudinally reciprocated on the arbor 152 against the force of coil spring 161 so that gear 150 may be brought out of engagement with pinion 149 so that the hub and the time dial 148 may be freely rotated. Arranged adjacent the periphery of the time dial 148 is a bracket 162 secured to the panel board 124. Etched upon the bracket 162 is an index marker 163 for purpose of setting the time dial 148. It will be understood that by grasping the thumb nut 149 and freeing the gear 150 from engagement with pinion gear 149, the time dial 148 may be adjusted so that the proper time of day on the time dial may be set opposite the index 163. In other words, the graduations on the time dial 148 actually represent the time of day and if this dial should get out of synchronism by reason of failure of power for the timing motor or the like, it may be again reset to the proper time in the manner just described.

Numeral 165 designates a pivoted lever pivoted at point 166 and having a shape generally as seen on Figure 1. The lever 165 has an angular portion 167 which forms a cam follower arranged to engage the peripheries of the half dials 155 and 156 which form cams. The lever 165 is continually biased in a counter-clockwise direction by a coil spring 168 and the lever has a generally horizontal portion 169 carrying mercury switch 170. The hub 151 is arranged to rotate in a counter-clockwise direction and whenever the cam follower 167 rides off the periphery of the shaded half dial, the coil spring 168 will rotate the lever 165 in a counterclockwise direction against a stop 171 causing opening of the mercury switch 170 which is normally closed whenever the cam follower 167 is following the periphery of the half dials. The mercury switch 170 forms a night shut-down switch for the system and in the description of the operation following the manner of setting the night shut-down adjustment and for restarting in the morning will be pointed out.

Numeral 173 is an electric time switch which may be of an approved conventional type and which is adjustable so as to close the electric circuit therethrough at a predetermined time and to again open it after it has been closed for a predetermined duration of time.

Power at suitable voltage for the relay 83 is supplied from a step-down transformer generally designated at 174 and comprising a primary winding 176 which may be connected to a suitable source of external power (not shown) and a secondary winding 177.

Operation

In my system with an outdoor temperature of 70°, the return line temperature should be substantially 70° indicating that no heating is required in the building. The temperature responsive mechanism 23 is primarily controlled by the return line temperature controller 30 and is compensated by the controller 42. With the parts in the position shown, these temperatures prevail and the sliders 35 and 41 are in the mid positions of their associated resistances and therefore the coils 24 and 25 of the balanced relay are equally energized. Assuming for the moment that the controller 42 is not present, if the return line temperature falls below 31 will contract moving slider 35 to the left along slide wire resistance 38 and slider 36 to the right along slide wire resistance 39. It will be understood that the potentiometer formed by the controller 30 acts as a voltage divider for the voltage available between wires 73 and 74 for energizing the respective coils 24 and 25. In other words, as slider 35 moves to the left, the voltage drop between slider 35 and wire 52 is increased and therefore this increased voltage is impressed upon the coil 25 between the wire 52 and wire 58 which connects to the slider 36. Similarly, movement of slider 35 to the left decreases the voltage impressed upon the coil 24. When the voltage impressed on coil 25 preponderates a predetermined amount, armature 26 will move to the right moving switch arm 27 so as to engage fixed contact 29. This will complete an energizing circuit for coil 62 which is as follows: from secondary winding 72 through wire 73, wire 78, wire 77, coil 62, wire 79, switch 21, fixed contact 29, wire 75, and wire 74 back to secondary winding 72. As soon as coil 62 is energized, switch arms 64 and 65 will move to the left engaging their respective fixed contacts. Upon closure of switch 64, a maintaining circuit for coil 62 is completed as follows: from secondary winding 62 through wire 73, wire 78, wire 77, coil 62, wire 79, wire 80, switch blade 64, wire 81, wire 52, wire 75, and wire 74 back to secondary winding 72. By reason of this maintaining circuit, coil 62 remains energized independently of the original circuit through which it was energized. Assume now that there is a rise in temperature of the return line 11 causing slider 35 to move to a position slightly beyond its original position. Energization of coil 24 will not preponderate over that of coil 25 and armature 26 will be moved to the left so that switch arm 27 engages fixed contact 28. An energizing circuit for neutralizing coil 63 will now be completed as follows: from secondary winding 72, wire 73, wire 78, coil 63, wire 76, fixed contact 28, switch blade 21, wire 79, wire 80, switch blade 64, fixed contact 66, wire 81, wire 52, wire 75, and wire 74 back to secondary winding 72. As soon as neutralizing coil 63 is energized, it will neutralize the effect of coil 62 upon the armature associated therewith and the switch arms 64 and 65 will disengage from their associated contacts. Opening of switch 64 will interrupt the above described circuits for both the coils 62 and 63. From the description so far, it will be understood that after coil 62 is once energized it does not become deenergized until switch blade 27 engages contact 28. It will be seen therefore that the controller 30 has a fixed operating differential which depends upon the sensitivity of the balanced relay coils 24 and 25. The relay comprising these coils is of such sensitivity that the slider 35 need move over only a small fraction of 75

the resistance 38 to cause actuation of the switch 27.

The fractional part of the resistance 38 over which the slider 35 need move in order to actuate switch 27 can be selected automatically by the compensating controller 42. In other words, the control point of the controller 30 can be shifted from one point on the resistance 38 to another by the controller 42. For example, should the outdoor temperature fall, it will indicate the need for a greater amount of heating and consequently that an increased amount of steam be supplied to the system. An increased supply of steam will mean that the temperature of condensate in the return line 11 will be higher. Therefore when the outdoor temperature falls, provision must be made for a higher return line temperature. Now as above described, the potentiometer formed by controller 42 is in parallel with controller 30. As outdoor temperature falls, slider 41 will move to the left along slide wire resistance 48. This controller will act as a second voltage divider tending to unbalance the energization of coils 24 and 25. As slider 41 moves to the left, it will be seen that it will bring about closure of switches 64 and 65 and in order to rebalance the coils 24 and 25, the slider 35 of controller 30 will have to move to the right, that is, the temperature affecting bulb 33 will have to rise causing slider 35 to move to the right to balance the leftward movement of slider 41 of compensating controller 42. It will be seen that the effect of this movement of the compensating controller will be to move the control point of controller 30 to the right to a higher temperature point on slide wire resistance 38. It follows therefore that the outdoor bulb 44 measures the heating load and the heat supply is adjusted accordingly by maintaining the corresponding necessary return line temperature.

40 The function of resistance 60 is to insure that controller 30 always dominates rather than controller 42. Resistance 60 limits the effect of controller 42 so that even if slider 41 is at one end or the other of resistance 48, controller 30 still operates to control relay 61 without slider 35 moving off resistance 38.

45 The resistance 39 is known as a corrector resistance and its purpose is to increase the amount of resistance in the connection between the junction of coils 24 and 25 and the slider 35 as the slider 35 moves in one direction or the other over resistance 38. The reason for the need of this corrector resistance is that as slider 35 moves to the left, for example, changing the voltage drops between wires 51 and slider 35 and between slider 35 and wire 52, the rate of change of voltage drops across the coils 24 and 25 changes at a greater rate. Therefore as sliders 35 and 36 move in one direction or the other, a part of resistance 39 is inserted in series with wire 58 and when the elements are properly proportioned, the rate of change of voltages across coils 24 and 25 is reduced to the desired rate whereby accurate control is secured.

50 From the foregoing, it should now be obvious that the switch 65 is closed at a predetermined temperature of the return line 11 which is adjusted in accordance with outdoor temperatures. As described above, as outdoor temperatures fall the return line temperature at which switch 65 closes is raised. Mercury switch 19 is a normally closed switch and mercury switch 170 is normally closed during the daytime. With these mercury switches closed, when switch 65 closes, a circuit

energizing the relay 83 is completed as follows: from switch blade 65 through wire 180, wire 181, wire 182, contact bracket 141, contact 143, contact 135, (these contacts are normally closed), screw 137, wire 183, coil 84, wire 184, secondary winding 177, wire 185, mercury switch 19, wire 186, wire 187, mercury switch 170, wire 188, wire 189 back to fixed contact 67. Upon energization of relay 83, switch blades 85 and 86 engage their associated contacts, the switch 86 completing an energizing circuit to the stoker 13 as follows: wire 190, which leads to a suitable source of external source of power, switch blade 86, fixed contact 88, wire 191, terminals 15 and 14 of the motor driving the stoker and wire 192 also leading to a suitable source of external power. Closure of switch 85 completes a maintaining circuit for the relay 83 which is controlled by switch 19 but which is independent of switch 65 and is as follows: from secondary winding 177 through wire 184, coil 84, wire 183, screw 137, contact strip 134, normally closed contacts 135 and 143, contact bracket 141, wire 182, wire 181, fixed contact 87, switch blade 85, wire 193, wire 188, mercury switch 170, wire 187, wire 186, mercury switch 19, and wire 185 back to secondary winding 177. Thus it will be seen that when the temperature responsive mechanism has energized the stoker, fuel will be continuously supplied to the furnace under the control of the pressure responsive switch 16 until sufficient boiler pressure has been built up so as to cause interruption of the above described maintaining circuit. A high enough boiler pressure will therefore be assured so that there will be no danger of radiators on upper floors not receiving an adequate supply of steam upon a thermostatic demand for heating.

When the relay 83 was energized, lever 91 was rotated in a counter-clockwise direction in a manner to latch the lever 123 in a raised position as already described in the structural part of the description. The cams 104 and 105 rotate constantly but because of the lever 123 being so latched in its upper position the position of the contacting mechanism operated by the cam followers is not changed as long as the parts remain in the last described position. The temperature responsive mechanism may become satisfied now at any time causing the switch 65 to open but the structure will remain in operation until at a predetermined boiler pressure the switch 16 is opened interrupting the above described maintaining circuit and deenergizing the relay 83. Switches 85 and 86 will now open and arm 89 will move to the right about its pivot disengaging blade 90 from lug 95. However, lever 91 will not now be returned to its original position under the influence of weight 94 tending to rotate it clockwise because the finger 97 is latched in a position to the left of the pointed end of latching member 131 with lever 123 in a raised position. Now the purpose of the timing mechanism 100 is in part to operate the structure at short intervals when there are no thermostatic demands for heating so as to keep the fire in the furnace from going out. In performing this intermittent operating function as will presently be described, the cams 104 and 105 actuate the contacting mechanism carried by the cam followers. But as just pointed out, this contacting mechanism is inactuable when the lever 123 is in its present upwardly latched position. Now at the time relay 83 is deenergized, the cams 104 and 105 may be in any position. Regardless of

what position they are in at the time of deenergization of relay 83, as soon as either one of the projections 109 or 110 on cam 104 engage the cam follower 121 the arbor 120 will be rotated clockwise moving the lever 123 with it sufficiently so that latching member 131 will be raised out of engagement with finger 97. Immediately upon this occurring, lever 91 will be rotated clockwise under the influence of weight 94 and will assume a position as shown in Figure 1. Now as soon as the projection 109 or 110 has passed the cam follower 121, the latter cam follower will be riding on a surface of cam 104 of larger diameter. Arbor 120 will now be free to be rotated in a counter-clockwise direction and therefore both the cam followers 121 and 122 will be free to drop into the drop-offs in the contours of their associated cams. Assuming now that for an appreciable time there are no thermostatic demands for heating. At a predetermined time after cam follower 121 has ridden over projection 109, for example, releasing lever 123, cam follower 121 will be in the position shown in Figure 1. Upon continued rotation now of the cams, cam follower 121 will drop into the drop-off 108 permitting arbor 120 to rotate slightly in a counter-clockwise direction. However, cam follower 122 will continue to follow the contour of cam 105 and will not rotate with cam follower 121. Upon rotation of arbor 120 with cam follower 121, bracket 140 will bring contacts 142 and 136 into engagement and bracket 141 will cause separation of contacts 143 and 135. Upon closure of contacts 142 and 136, an energizing circuit for relay 83 is completed as follows: from secondary 177 through wire 184, coil 84, wire 183, screw 137, contact bracket 134, contacts 136 and 142, contact bracket 140, wire 186, mercury switch 19, wire 185 back to secondary winding 177. Energization of relay 83 will cause closure of switches 85 and 86, closure of switch 86 energizing the stoker motor through the circuit already described. Upon energization of relay 83 this time, however, the lever 91 will not be permitted to be rotated in a counter-clockwise direction in the manner above described for the following reason: at the time that cam follower 121 drops into the drop-off 108 of cam 104, as pointed out above, arbor 120 is rotated slightly in a counter-clockwise direction and lever 123 rotates with arbor 120 causing the latch member 131 to drop down on the left side of finger 97 so that finger 97 abuts against the right hand edge of the downwardly extending portion of latch 131. Lever 123 and latch 131 now prevent counter-clockwise movement of lever 91 upon energization of relay 83 and while arm 89 moves to the left and blade 90 engages lug 95 the blade 90 merely flexes not moving the lug 95 to the left.

The stoker is now in operation and will continue in operation for a predetermined number of minutes until the cam follower 122 drops in the first drop-off 106 of cam 105. This will happen at an adjustable period ranging from 1 to 7 minutes after cam follower 121 dropped into drop-off 108 starting the stoker. In dropping into the first drop-off 106, cam follower 122 will rotate slightly in a counterclockwise direction about the arbor 120 which does not rotate at this time (it will be recalled that coil spring 130 biases cam follower 122 about the arbor 120 in a counterclockwise direction against the contour of cam 105). When cam follower 122 drops into the first drop-off 106 as described, the contact strip 134 carried thereby will be moved so as to

separate contacts 136 and 142 but the right end of contact strip 134 will not move upward sufficiently to close contacts 135 and 143. Upon disengagement of contacts 142 and 136 the above described circuit therethrough which energized relay 83 by reason of the operation of the cam and contacting mechanism will be interrupted. Relay 83 will now be deenergized and switches 85 and 86 will open causing termination of operation of the stoker. It will be understood that cam follower 122 will remain in the first drop-off 106 for a very short time of only a few seconds and that during this time both the contacts 142 and 136 and the contacts 143 and 135 will be separated. The reason for this construction wherein both sets of contacts are separated for a brief interval is to permit relay switch 85 to open before the same maintaining circuit as was described above has a chance to be completed through the switch 85 and the contacts 143 and 135. After this short interval of a few seconds cam follower 122 drops into the second drop-off 106 and rotating slightly further in a counter-clockwise direction thereby moving the right end of contact strip 134 upwardly so as to bring contacts 135 and 143 into engagement. From the foregoing, it will be understood that the stoker is energized in response to the timing mechanism for a period of time determined by the angular spacing between the drop-off 108 of cam 104 and the first drop-off 106 of cam 105. The duration of timed operation of the stoker can be adjusted by adjusting the angular spacing between these drop-offs by adjusting the cam 104 on the arbor 120 relatively to the cam 105. Thus by rotating cam 104 in a counter-clockwise direction on the arbor 120 with respect to cam 105 as seen in Figure 1, the angular spacing between drop-offs 108 and 106 is made smaller as the duration of timed stoking operation is correspondingly shortened. When this latter adjustment is made, it is seen that the graduations on the cam 104 adjacent the pointer 119 will bring a smaller number indicating a smaller number of minutes of timed stoker operation opposite to the pointer. When it is desired to manually actuate the contacting mechanism, the cams can be rotated together on the arbor 120 by grasping the handle 118 and applying a torque thereto.

From the foregoing it will be apparent that when the stoker is energized in response to a thermostatic demand for heat the stoker will remain in operation until stopped by the pressure responsive switch. On the other hand, if the stoker is energized by the automatic timing mechanism, the latter mechanism will also de-energize the stoker independently of the pressure switch.

Referring now to the timing mechanism whereby I automatically actuate the night shut-down switch 170, let it be assumed that it is desired to shut down the system at 8 p. m. and restart it at 6 a. m. Suppose the operator is making this adjustment at 10 a. m., if so he grasps the thumb nut 159 and in the manner described sets the figure 10 on the unshaded half of the timed dial 148 opposite the index 163. Of course, if the proper time of day on the dial 148 is already opposite the index 163 this adjustment need not be made. If this adjustment is made at some time in the afternoon, that is, between noon and midnight, the proper hour on the shaded half of the time dial 148 is set opposite the index 163. The above adjustment having been made, the thumb nut 159 is loosened and the

figure 8 on the shaded half dial is set opposite the pointer 158 and the figure 6 on the unshaded half dial is set opposite the pointer 158 (see Figure 1). The thumb nut 159 is then tightened with the half dials in these set positions. It will be seen that the angular extent of the circular periphery of each of the half dials 155 and 156 is substantially half of that of the twenty-four hour dial 148. In other words, it would take substantially twelve hours for the cam follower 167 to traverse the entire circular periphery of the shaded half dial from one extremity to the other. With the above described adjustments having been made, it will be seen in Figure 1 that the cam follower 167 is substantially opposite the figure 10 on the shaded half dial. Thus with the dials rotating counter-clockwise, it will be substantially ten hours after the time of setting that the cam follower 167 will drop off the shaded half dial. With settings being made at 10 a. m., it follows that at 8 p. m. cam follower 167 will ride off the edge of the shaded half dial and lever 165 will be rotated counter-clockwise so as to open the switch 170. When switch 170 is open the system may not be energized in response to the thermostatic mechanism inasmuch as the above described circuit controlled by switch 65 passes through the mercury switch 170. However, opening of mercury switch 170 does not interfere with the timed operation of the stoker for purposes of maintaining a fire within the furnace. Now if the half dials had been adjusted relative to each other so that they were coincidentally superimposed upon each other, it will be seen that substantially twelve hours would elapse after cam follower 167 rode off the shaded half dial before it would be again engaged by the half dials. With such a setting the mercury switch 170 would be again actuated, this time to closed position twelve hours after the night shut-down time which would make it 8 a. m.

However, inasmuch as figure 6 on the unshaded half dial has been set opposite the pointer 158, it is seen that the unshaded half dial is spaced substantially two hours in a counter-clockwise direction from the shaded half dial. Therefore with the dials rotating in a counter-clockwise direction after the cam follower 167 rides off the shaded half dial it will be substantially ten hours until the unshaded half dial engages the cam follower and repositions the lever 165 into closed position of the switch 170. Night shut-down having occurred at 8 p. m. when cam follower 167 rode off the shaded half dial, ten hours later will make the time of closing of switch 170 6 a. m. the following morning.

The bracket 162 and cam follower 167 might take other relative positions with respect to the various dials. The position of the pointer 158 is fixed relative to the twenty-four hour dial 148 but this pointer also might take other relative positions depending upon the position of the cam follower 167 with respect to the dials. With the elements 163 and 167 taking the relative positions shown in Figure 1, the position of the pointer 158 becomes determinate in the following manner: for example, suppose the figure 12 on the unshaded half of dial 148 (representing 12 a. m. noon) were set opposite the index 163 by rotating dial 148 two hours in a counter-clockwise direction from the position shown, and suppose further that it were desired that night shut-down should occur twelve hours later than this time of 12 a. m. noon. The shaded half dial would then be set with cam follower 167 sub-

stantially adjacent the figure 12 on the shaded half dial because it would be necessary for the cam follower to traverse the entire circular periphery of the shaded half dial which requires substantially twelve hours. Night shut-down would then occur at 12 p. m. midnight and therefore the pointer 158 would be pointing to the figure 12 on the shaded half dial (recalling that dial 148 and pointer 158 which moves with it have been rotated two hours in a counter-clockwise direction from the position shown), and would correspondingly be pointing in the direction of the cam follower 167. The figure 12 on the unshaded half of dial 148 now being opposite the index 163, the figure 4 on the unshaded half of dial 148 would be adjacent the cam follower 167 and obviously it follows that the pointer 158 will be pointing at figure 4 on the unshaded half of dial 148 as seen on Figure 1. Thus it is seen that the pointer 158 has a definite proper position on the hub 151 depending upon the relative positions of the other elements of the apparatus.

The time switch 173 is adjusted so as to close the circuit therethrough at the same time in the morning that the mercury switch 170 becomes closed. It will be seen that the time switch 173 closes the circuit controlled by switch 65, the latter switch being connected across the wires leading to the time switch and that therefore when mercury switch 170 closes in the morning at the same time the circuit normally controlled by switch 65 is closed irrespective of whether or not the thermostatic apparatus is calling for heat. The time of closing of the time switch 173 and mercury switch 170 in the morning marks the beginning of a period commonly referred to in the art as morning pick-up period. The time switch 173 maintains the circuit therethrough closed for an adjustable period of time which may be of a duration of two hours, for example, but can be adjusted by the janitor to be of a duration normally sufficient depending on the outside weather conditions to bring the temperature up to the normal daytime level after the night shut-down. During the time that switch 173 is closed the structure is operated continuously or until it is shut down by the pressure switch 16. The circuit through time switch 173 remaining closed, it is seen that if the stoker is shut down by pressure switch 16 it may be again started by closure of pressure switch 16, the boiler thus operating at its high limit capacity all during the time that time switch 173 is closed. After time switch 173 opens the apparatus is, of course, again under the normal control of the thermostatic apparatus 23 and the automatic time mechanism provided for intermittent operation of the stoker.

From the foregoing it should be apparent to those skilled in the art that I have provided a highly novel and useful control system for heating plants. My system provides positive control insuring that heat is adequately supplied to all parts of the system upon each demand for heating by the thermostatic apparatus which apparatus is compensated so as to demand heat in accordance with the load as determined by outdoor temperature.

The interlocking relation between my automatic timing and thermostatic control mechanism is unique in that when the firing apparatus is started in response to the thermostatic mechanism control shifts to the pressure switch but if the firing apparatus is started by the automatic timing mechanism for fire maintaining purposes

control does not shift to the pressure switch but the timing apparatus can stop the firing apparatus after a predetermined period of operation. Thus the apparatus automatically and properly chooses whether or not control of the firing device is to be shifted to the pressure switch responsive to boiler pressure after the firing device has been started. By reason of my particular combination and operation thereof heating can be more uniformly and adequately controlled and in practice my system has been found to effect substantial economies in fuel consumption.

While I have described in detail the structure and operation of a preferred form of my invention, I desire that I be protected on all its novel features and aspects. Therefore I am to be limited not by my disclosure which is illustrative and exemplary but only as determined by the scope of the appended claims.

20 I claim as my invention:

1. In a heating system employing a vaporizable heating medium, in combination, heating means including an electrically energizable device, control apparatus comprising means responsive to 25 the temperature of the heating medium, means responsive to the pressure of the heating medium, an electrical relay controlling said device, said temperature responsive means controlling said relay to start said device and said control apparatus embodying means whereby upon starting of said device a maintaining circuit for said relay controlled by said pressure responsive means is established, automatic timing mechanism controlling said relay for operating said device at intervals to maintain a limited amount of heat in the heating means, said timing mechanism comprising contacting means actuatable thereby, said contacting means controlling said maintaining circuit, means operated by said relay rendering said contacting means inactuable to affect said relay when said relay is energized by said temperature responsive means whereby said timing mechanism will not interrupt said maintaining circuit, said means operated by said relay being ineffective to render said contacting means inactuable to affect said relay when said relay is energized by said timing mechanism.

2. In a heating system employing a vaporizable heating medium, in combination, heating means including an electrically energizable device, control apparatus comprising means responsive to the temperature of the heating medium, means responsive to the pressure of the heating medium, an electrical relay controlling said device, said temperature responsive means controlling said relay to start said device and said control apparatus embodying means whereby upon starting of said device a maintaining circuit for said relay controlled by said pressure responsive means is established, automatic timing mechanism controlling said relay for operating said device at intervals to maintain a limited amount of heat in the heating means, said timing mechanism comprising contacting means actuatable thereby, said contacting means controlling said maintaining circuit, means operated by said relay rendering said contacting means inactuable to affect said relay when said relay is energized by said temperature responsive means whereby said timing mechanism will not interrupt said maintaining circuit, said contacting means having a member cooperating with said relay operated means in such a manner that when said timing mechanism actuates said contacting means to energize said

relay said member prevents said relay operated means from rendering said contacting means inactuable to affect said relay.

3. In a heating system employing a vaporizable heating medium, in combination, heating means including an electrically energizable device, control apparatus comprising means responsive to the temperature of the heating medium, means responsive to the pressure of the heating medium, an electrical relay controlling said device, said 10 temperature responsive means controlling said relay to start said device and said control apparatus embodying means whereby upon starting of said device a maintaining circuit for said relay controlled by said pressure responsive means is established, automatic timing mechanism controlling said relay for operating said device at intervals to maintain a limited amount of heat in the heating means, said timing mechanism comprising a cam and contacting means actuable thereby said contacting means controlling said maintaining circuit, means operated by said relay rendering said contacting means inactuable to affect said relay when said relay is energized by said temperature responsive means whereby said timing mechanism will not interrupt said maintaining circuit, said contacting means having a member cooperating with said relay operated means in such a manner that when said cam actuates said contacting means to energize said relay said member prevents said relay operated means from rendering said contacting means inactuable to affect said relay, said timing mechanism including means for initiating operation of said device and for terminating operation of said device after a period of predetermined duration.

4. In a heating system employing a vaporizable heating medium, in combination, heating means including an electrically energizable device adapted for cycling operation and means for circulating heating medium from said heating means to spaces to be heated, means indicative of the temperature of heating medium returning to said heating means for energizing said device to initiate an operating cycle of said system, means responsive to a pressure condition of said medium indicative of circulation thereof substantially throughout the system, control means whereby after said device is energized by said temperature indicative means, it remains energized until a predetermined pressure condition is sensed by said pressure responsive means, said device being then deenergized terminating the cycle, timing means for continuously energizing said device for a period of time unless said pressure responsive means is satisfied, said device being energized during said period of time if said condition responsive means is indicating a need for further heat, and timing means for periodically energizing said device for relatively short intervals.

5. In a heating system employing a vaporizable heating medium, in combination, heating means including an electrically energizable device, control apparatus comprising means responsive to the temperature of the heating medium, means responsive to the pressure of the heating medium, an electrical relay controlling said device, said temperature responsive means controlling said relay to start said device, control apparatus embodying means whereby after starting of said device it is maintained in operation under control of said pressure responsive

means, said last means having a preadjusted pressure setting at which pressure operation of said device is terminated, timing means for continuously energizing said relay for predetermined periods, said device being continuously energized during said periods unless said pressure responsive means is satisfied, and timing means for periodically energizing said device for intervals of relatively short duration.

6. In a heating system employing a vaporizable heating medium, in combination, heating means including an electrically energizable device, control apparatus comprising means responsive to the temperature of the heating medium, means responsive to the pressure of the heating medium, and an electrical relay controlling said device, said temperature responsive means controlling said relay to start said device and said control apparatus embodying means whereby upon starting of said device a maintaining circuit for said relay controlled by said pressure responsive means is established, and automatic means for intermittently energizing said relay and for deenergizing said relay to operate said device for maintaining a limited amount of heat in said heating means, said automatic means including mechanism associated with the relay whereby the automatic means normally can control said maintaining circuit but not if the relay was energized by the temperature responsive means, so that the automatic means does not interrupt the maintaining circuit when the device has been started by the temperature responsive means.

7. In a heating system employing a vaporizable heating medium, in combination, heating means including an electrically energizable device adapted for cycling operation and means for circulating heating medium from said heating means to spaces to be heated, means indicative of the temperature of heating medium returning to said heating means for energizing said device to initiate an operating cycle of said system, means responsive to a pressure condition of said medium indicative of circulation thereof substantially throughout the system, control means whereby after said device is energized by said temperature indicative means, it remains energized until a predetermined pressure condition is sensed by said pressure responsive means, said device being then deenergized terminating the cycle, timing means for terminating control by said temperature indicative means for predetermined periods and for continuously energizing said device for other predetermined periods unless said pressure responsive means is satisfied, and timing means for periodically energizing said device for relatively short intervals.

8. In a heating system employing a vaporizable heating medium, in combination, heating means including an electrically energizable device, control apparatus comprising means responsive to the temperature of the heating medium, means responsive to the pressure of the heating medium, and an electrical relay controlling said device, said temperature responsive means controlling said relay to start said device and said control apparatus embodying means whereby upon starting of said device a maintaining circuit for said relay controlled by said pressure responsive means is established, and automatic means for intermittently energizing said relay and for deenergizing said relay to operate said device for maintaining a limited amount of heat in said heating means, said automatic means nor-

mally controlling said maintaining circuit and means associated with said relay whereby said automatic means is rendered ineffective to interrupt said maintaining circuit when said relay is energized in response to said temperature responsive means.

9. In a heating system employing a vaporizable heating medium, in combination, heating means including an electrically energizable device, control apparatus comprising means responsive to the temperature of the medium returning to the heating means, means responsive to the pressure of the heating medium, an electrical relay controlling said device, said temperature responsive means controlling said relay to start said device and said control apparatus embodying means whereby upon starting of said device a maintaining circuit for said relay is established whereby said relay remains energized irrespective of said temperature responsive means, said pressure responsive means controlling said relay and being operable to de-energize it at a predetermined pressure, said control apparatus including switching means for energizing said relay irrespective of said temperature responsive means unless deenergized by said pressure responsive means, and timing means for intermittently energizing said device for predetermined intervals.

10. In a heating system employing a vaporizable heating medium, in combination, heating means including an electrically energizable device, control apparatus comprising means responsive to the temperature of the heating medium, means responsive to the pressure of the heating medium, an electrical relay controlling said device, said temperature responsive means controlling said relay to start said device and said control apparatus embodying means whereby upon starting of said device a maintaining circuit for said relay controlled by said pressure responsive means is established, automatic timing mechanism controlling said relay for operating said device at intervals to maintain a limited amount of heat in the heating means, said timing mechanism comprising contacting means actuatable thereby, said contacting means controlling said maintaining circuit to enable said timing mechanism to deenergize as well as to energize said relay.

11. In a heating system employing a vaporizable heating medium, in combination, heating means including an electrically energizable device, control apparatus comprising means responsive to the temperature of the medium returning to the heating means, said temperature responsive means including a switch adapted to close at a predetermined temperature, means responsive to the pressure of the heating medium comprising a switch adapted to be closed at a predetermined pressure, an electrical relay controlling said device, said relay comprising a main switch and an auxiliary switch, both of said switches adapted to be closed when the relay is energized and opened when the relay is de-energized, said temperature responsive means controlling a circuit for energizing said relay when the switch of said temperature responsive means is closed, said main switch of said relay controlling said electrically energizable device and said auxiliary switch controlling a maintaining circuit for said relay which is established upon energization of the relay to cause the relay to remain energized after having become energized even though the switch of said temperature responsive means is closed.

ture responsive means is opened and said pressure responsive means being arranged to cause deenergization of said relay when the switch of said pressure responsive means is opened.

5 12. In a heating system employing a vaporizable heating medium, in combination, heating means including an electrically energizable device, control apparatus comprising means responsive to the temperature of the medium returning to the heating means, said temperature responsive means including a switch adapted to close at a predetermined temperature, means responsive to the pressure of the heating medium comprising a switch adapted to be closed at a predetermined pressure, an electrical relay controlling said device, said relay comprising a main switch and an auxiliary switch, both of said switches adapted to be closed when the relay is energized and opened when the relay is de-energized, said temperature responsive means controlling a circuit for energizing said relay when the switch of said temperature responsive means is closed, said main switch of said relay controlling said electrically energizable device and said auxiliary switch controlling a maintaining circuit for said relay which is established upon energization of the relay to cause the relay to remain energized after having become energized even though the switch of said temperature responsive means is opened, said pressure responsive means being arranged to cause deenergization of said relay when the switch of said pressure responsive means is opened, and said control apparatus including timing means for intermittently energizing and deenergizing said device.

13. In a heating system employing a vaporizable heating medium, in combination, heating means including an electrically energizable device, control apparatus comprising means responsive to the temperature of the medium returning to the heating means, said temperature responsive means including a switch adapted to close at a predetermined temperature, means responsive to the pressure of the heating medium comprising a switch adapted to be closed at a predetermined pressure, an electrical relay controlling said device, said relay comprising a main switch and an auxiliary switch, both of said switches adapted to be closed when the relay is energized and opened when the relay is de-energized, said temperature responsive means controlling a circuit for energizing said relay wherein the switch of said temperature responsive means is closed, said main switch of said relay controlling said electrically energizable device and said auxiliary switch controlling a maintaining circuit for said relay which is established upon energization of the relay to cause the relay to remain energized after having become energized even though the switch of said temperature responsive means is opened, said pressure responsive means being arranged to cause deenergization of said relay when the switch of said pressure responsive means is opened, said control apparatus including timing means for intermittently energizing and deenergizing said device, and means for maintaining said relay energized irrespective of said temperature responsive means as long as the switch of said pressure responsive means is closed.

14. In a heating system employing a vaporizable heating medium, in combination, heating means including an electrically energizable device, control apparatus comprising means responsive to the temperature of the heating me-

dium at a point remote from the heating means at which it has given up at least a part of its heating effect, means responsive to the pressure of the heating medium, an electrical relay controlling said device, said temperature responsive means controlling said relay to start the device, control apparatus embodying means whereby after starting of said device it is maintained in operation under control of said pressure respon-

5 sive means, said last means having a pre-adjusted pressure setting at which pressure operation of said device is terminated, means for continuously energizing said relay for periods of time unless said pressure responsive means becomes satisfied within said periods, and timing means for periodically energizing said device for intervals of relatively short duration.

JOSEPH T. LEWANDOWSKI.
